CLAIM

The ornamental design for a suturing guide, substantially as shown and described.

DESCRIPTION

FIG. 1 is an isometric view of a suturing guide showing our new design, the needle shown in broken lines for illustrative purpose only and forms no part of the claimed design;

FIG. 2 is a front elevational view thereof;

FIG. 3 is a right side elevational view, the left side is identical thereof;

FIG. 4 is a rear elevational view thereof;

FIG. 5 is a top plan view thereof; and,

FIG. 6 is a bottom plan view thereof.

It is understood that a suturing guide tube shown broken away in the middle to indicate indeterminate length.
